UNITED STATES PATENT OFFICE.

CLINTON A. TOWER, OF CLEVELAND, OHIO.

HUB-BAND CAP.

SPECIFICATION forming part of Letters Patent No. 729,518, dated May 26, 1903.

Application filed December 26, 1902. Serial No. 136,550. (No model.)

To all whom it may concern:

Be it known that I, CLINTON A. TOWER, of Cleveland, in the county of Cuyahoga and State of Ohio, have invented a new and useful Hub-Band Cap, of which the following is a full, clear, and exact description, reference being had to the accompanying drawings, forming part of this specification, in which—

Figure 1 shows in side elevation, partly in section, a hub-band cap constructed in accordance with my invention. Figs. 2 and 3 are horizontal cross-sections on the line II II of Fig. 1, showing the fastening device of the cap in unlocked and in locked position, respectively. Fig. 4 is a vertical section on the line IV IV of Fig. 3, showing the cap in locked position. Fig. 5 shows the cap in vertical cross-section. Fig. 6 is a horizontal section showing a modification of my invention. Fig. 7 is a vertical section showing another form of tongue. Fig. 8 shows in detail the tongue illustrated in Fig. 7. Fig. 9 shows in vertical section a cap having the locking-tongues secured in another way. Fig. 10 shows in plan view, and Fig. 11 in vertical section, a further modification of the attachment. Figs. 12 and 13 show in plan view and side elevation a modified construction of locking-tongue, part of the cap in Fig. 12 being broken away to expose the tongue.

It is of special importance that the caps for the hub-bands of vehicles should be provided with fastening devices of simple construction, and that although readily detachable they may be capable of being secured very firmly to the band, for they are subject to rough usage and unless strongly held will rattle and are apt to jar loose. It is also of importance that the devices used for holding the cap shall not disfigure the hub-band, so that, if desired, the band when used without a cap shall not present an unsightly appearance.

My invention is designed to afford a cap having these features. It has the further advantage that all the members of the cap are fixed together and constitute a unit. It is of the simplest possible construction and when applied to the hub-band is held firmly in place.

My invention consists in a hub-band having a cap provided on its inner surface with fastening-tongues, preferably extending along the periphery of the cap and made of resili-

ent material, preferably of sheet metal set edgewise relatively to the cap and adapted to engage lugs formed on the interior of the band. The surface of the tongues which engage the lugs is inclined, so that the turning of the cap will draw it firmly to its seat on the hub-band.

In Figs. 1 to 5 of the drawings, 2 is the hub-band having on the interior lugs 3 3, preferably cast integral therewith, and the outer edge of the band may be beveled, as shown, in order to conceal the lugs when no cap is used and to facilitate the application of the cap. The cap 4 is a disk, preferably also of cast metal, adapted to fit the end of the band, and on its inner surface are tongues 5 5, preferably made of sheet-steel, which may be fixed to the cap by a transverse base portion 6, set between lips 7 7, which are bent over the portion 6, as shown, thus securely fixing the tongues to the cap as if they were a single piece. The tongues may be made integral with the cap, if desired. They extend from the base portions 6 along the periphery of the cap, and their edges next to the cap are somewhat inclined and are preferably formed with notches 8 8, adapted to engage the lugs 3 3. To apply the cap, it is fitted to the band as shown in Fig. 2, so that the tongues shall enter the band, and the cap is then turned, so as to cause the tongues to pass under the lugs, which, acting on the inclined edges of the tongues, draw the cap inwardly with a spring action, and when the notched portions reach the lugs they engage the same and hold the cap with great security. The cap is removed by rotating it forcibly in the reverse direction and then withdrawing it outwardly. The tongues 5 5 are preferably placed as shown in Figs. 2 and 3, so that their outer ends bear laterally against the sides of the hub-band, on which they exert a spring-pressure, and aid in preventing the cap from rattling.

In Fig. 6 the tongues 5' instead of taking under the lugs 3' 3' have holes b formed in the sides of the tongues, and in Figs. 7 and 8 the tongues are provided with inclined lateral grooves b' and are corrugated or provided with holes or depressions b''. The lugs 3 take into the grooves or holes, and when the cap is turned they draw it firmly to its seat.

In Fig. 9 the tongues 5 are like the tongues

of Fig. 1; but they are held to the cap by having portions *c* extending through holes in the cap and upset in the manner of rivets on the upper surface.

5 In Figs. 10 and 11 the tongues are held to vertical posts on the cap by rivets *d d*.

In Figs. 12 and 13 the tongues *5^b* are set in the same general plane with the cap, being held thereto by lips *7'*, as in Fig. 1. The outer ends of the tongue are inclined in the manner of a spiral and are adapted to take under the lugs *3 3* and have notches or corrugations at the margin to aid in holding them.

Other modifications may be made in the details of the device, since

What I claim is—

1. A hub-band having an interior lug and a cap provided on its inner face with a fastening-tongue having an inclined portion adapted to engage the lug, substantially as described.

2. A hub-band having an interior lug and a cap provided on its inner face with an inclined fastening-tongue extending along the periphery of the cap and adapted to engage the lug; substantially as described.

3. A hub-band having an interior lug, and a cap provided on its inner face with a fastening-tongue extending along the periphery of the cap and adapted to engage the lug, said tongue being set edgewise and inclined on the edge next to the lug; substantially as described.

4. A hub-band having an interior lug and a cap provided on its inner face with a fastening-tongue adapted to engage the lug, said tongue being inclined and notched on the edge next to the lug; substantially as described. 35

5. A hub-band having an interior lug, and a cap provided on its inner face with an inclined fastening-tongue extending along the periphery of the cap and adapted to engage the lug, said tongue having a lateral spring bearing against the hub-band; substantially as described. 40

6. A hub-band having interior lugs, and a cap provided with fastening-tongues which extend along the periphery of the cap, and an intermediate base portion extending transversely to the said tongues and connecting them, said base portion being fixed to the cap; substantially as described. 45

7. A hub-band having interior lugs, and a cap provided with fastening-tongues which extend along the periphery of the cap, and an intermediate base portion extending transversely to the said tongues and connecting them, said base portion being fixed to the cap by lips on the cap; substantially as described. 55

In testimony whereof I have hereunto set my hand.

CLINTON A. TOWER.
